J. A. PHILLIPS.

LIFTING JACK.

APPLICATION FILED MAY 21, 1908.

900,200.

Patented Oct. 6, 1908.

UNITED STATES PATENT OFFICE.

JOHN A. PHILLIPS, OF BLOOMFIELD, INDIANA.

LIFTING-JACK.

No. 900,200.

Specification of Letters Patent.

Patented Oct. 6, 1908.

Application filed May 21, 1908. Serial No. 434,124.

To all whom it may concern:

Be it known that I, JOHN A. PHILLIPS, citizen of the United States, residing at Bloomfield, in the county of Greene and State of Indiana, have invented certain new and useful Improvements in Lifting-Jacks, of which the following is a specification.

This invention comprehends certain new and useful improvements in lifting jacks, of the class known as lever bar, and clutch loop that embody a bar or standard and a pair of runners one of which is arranged to clutch the standard while the other is being raised, so as to effect an intermittent climbing movement upon the standard, and the present invention has for its primary object, a simple, durable and efficient construction of lifting jack of this character which may be cheaply manufactured and easily assembled and disassembled, those parts of the jack upon which the strain or wear is not mainly imposed, being formed preferably of cast iron or the like, while those parts upon which the strain comes are composed of steel, thereby enabling a strong structure to be produced at a relatively low cost; and another object of this invention is an improved construction of device of this character which will be positive and sure in its action and not liable in any degree to accidentally lower the load that is being raised.

With these and other objects in view, as will more fully appear as the description proceeds, the invention consists in certain constructions, arrangements and combinations of the parts that I shall hereinafter fully describe and claim.

For a full understanding of the invention, reference is to be had to the following description and accompanying drawings in which:

Figure 1 is a side elevation of a lifting jack embodying the improvements of my invention; the lower runner being shown in section. Fig. 2 is an enlarged sectional view of a portion of the jack, the section being taken through the upper runner; Fig. 3 is a horizontal section on the line 3—3 of Fig. 2. Fig. 4 is a detail sectional view through the lower runner, on an enlarged scale; Fig. 5 is a detail perspective view of the locking dog of the upper runner; and Fig. 6 is a detail sectional view on the line 6—6 of Fig. 1.

Corresponding and like parts are referred to in the following description and indicated

in all the views of the drawings by the same reference characters.

Referring to the drawings, the numeral 1 designates the standard of my improved lifting jack which is preferably constructed of 60 steel channeled on both sides and which may be secured at its lower end to the foot or base 2 of any desired construction. Preferably the standard 1 is secured at its upper end to a lifting handle 3 by which the device may 65 be carried from place to place, said handle embodying a wire clamp 4 and being formed with a vise jaw 5, said vise jaw being designed to coact with a corresponding vise jaw 6, on the upper runner 7 of the jack, and 70 the wire clamp 4 being designed to coact with a wire clamp 4^a on the said upper runner. By means of these accessories, the jack may be used as a wire stretcher or as a vise in addition to its primary function as a lifting or 75 hoisting apparatus.

8 designates the lower runner. The said lower runner 8 is mounted to move longitudinally on the standard 1 and is formed in its rear side with a recess 9 in which a toothed 80 block 10 is rigidly connected, as by a rivet or the like, said toothed block being preferably formed of tool steel in contradistinction to the cast material of which the runner itself is formed and the teeth of the block being 85 designed to engage the teeth 11 formed in the rear edge of the standard 1, as clearly illustrated in the drawings.

The lower runner 8 is hollow in its front side and is formed with a depending nipple 90 12 designed to hold in place the upper end of a coil expansion spring 13. The lower end of the spring 13 fits around a corresponding nipple 14 formed on the lower extremity or arm 15 of an L shaped pitman fulcrumed at 95 its elbow in the forward hollow portion of the lower runner 8 as indicated at 17. The pitman 16 projects upwardly into the hollow front portion of the upper runner 7 and is connected to a wrist pin 18 formed on the 100 operating lever 19, said lever being angular as shown and being fulcrumed at one end on the upper runner 7 as indicated at 20.

21 designates the preferably wooden handle portion of the operating lever.

22 designates the bearing surface of the upper runner upon which the load is placed, the rear side of said bearing surface preferably terminating in an upwardly projecting spur 23 which may be bent slightly inward 110

whenever necessary to take up any wear so as to properly bear against the front edge of the standard and which also serves as a rear abutment for the vehicle axle or other load imposed upon the bearing surface 22, to prevent the same from engagement with the standard.

The upper runner 7 is formed in its rear side with a cavity 24 in which the preferably 10 steel block 25 is received, said block being secured in place by transverse rivets or similar fastening means. The block 25 is formed with a chamber 26 which faces forwardly as shown and which is designed to accommodate the locking dog 27 of the upper runner said dog being formed with a toothed upper end 28 designed to engage the teeth 11 of the standard. The dog 27 is supported at its lower end in a socket formed for it by the 20 upwardly projecting lower extremity 29 of the block 25. A preferably steel spring 30 which is of V-shape, in the present instance, with its two leaves or members integrally connected together, is received in the chamber 26 back of the dog 27 and exerts a tension to press the dog forwardly into engagement with the teeth of the standard 1.

In order to hold the dog 27 retracted in the chamber 26 out of engagement with the 30 teeth 11, the said dog is formed in its front face with a recess 31. A cross bar 32 fits in said recess and extends outwardly through laterally elongated slots 33 formed in the said walls of the runner. The bifurcated releasing lever 34 has its two arms fulcrumed at their forward extremities on the ends of said cross-pin 32. The lever 34 is formed with an apertured finger piece 35 by which it may be pressed downwardly so as to ride 40 with a cam action on the outer rear inclined wall of the upper runner 7 so as to spring the dog 27 backwardly, the said lever finally finding lodgment in the groove 36 formed in the rear wall of the runner so as to lock the 45 lever in its released position, with the dog fully retracted.

37 designates a steel piece which is riveted or otherwise fastened in the runner 7 below the block 25 in engagement with the lower 50 end of the block, so as to assist in supporting the same.

In the practical operation of my improved lifting jack, it is evident from the foregoing description in connection with the accompanying drawing that by imparting a vertically oscillating movement to the actuating lever 19, the runners will alternately grip the standard, first one and then the other being raised so as to impart an upward movement 55 to the load. In order to slide the runners downwardly upon the standard, it is only necessary to swing the releasing lever 34 downwardly so as to retract the dog in the chamber 26 and to then raise the operating 60 lever 19 so as to lower the upper runner until

its lower end comes in contact with the lug 8^a projecting upwardly from the rear side of the lower runner 8 whereupon the lower runner 8 will be caused to rock rearwardly so as to cause its toothed block 10 to move 70 out of engagement with the teeth 11 of the standard and both runners may then be slid freely down the standard.

As best seen in Fig. 6 the operating lever 19 is formed with a hollow cylindrical trunnion 19^a which fits within a bearing opening in the runner as indicated at 20. A screw 20^a works into the threaded bore 20^b of the trunnion, a washer being interposed between the head of the screw and one side of the runner, the purpose of said screw and washer being to hold the operating lever securely in place, and to take up by its tension the wear.

Having thus described the invention, what is claimed as new is:

1. A lifting jack comprising a standard, upper and lower runners mounted to slide on said standard, an operating lever fulcrumed on the upper runner and having a pitman connection with the lower runner, means carried by the lower runner for gripping the standard, the upper runner being formed with a cavity, a block rigidly secured in said cavity, and formed with a chamber, and an outwardly spring pressed dog mounted in 95 said chamber and arranged to engage the standard.

2. A lifting jack, comprising a standard, upper and lower runners mounted to slide on said standard, the lower runner being arranged to grip the standard, an operating lever fulcrumed on the upper runner and having a pitman connection with the lower runner, the upper runner being formed with a cavity, a block rigidly secured in said cavity and formed with a forwardly facing chamber and an upwardly facing socket in the lower end of the chamber, and an outwardly spring pressed dog mounted in said chamber and supported with its lower end in said 100 socket and arranged for engagement with said runner.

3. A lifting jack, comprising a standard, upper and lower runners mounted to slide on said standard, the lower runner being arranged to clutch the standard, an operating lever fulcrumed on the upper runner and having a pitman connection with the lower runner, a dog mounted in the upper runner and spring pressed into engagement with the 115 standard, a cross-pin interposed between a portion of the dog and the adjacent edge of the standard, the upper runner being formed with laterally elongated slots, accommodating the ends of said pin and the runner being 120 further formed with an inclined outer wall, and a releasing lever forked to embrace the runner and pivotally connected to the ends of said pin and arranged to ride upon the inclined wall of the runner whereby to draw 125 130

the dog backwardly against its spring tensioning means.

4. A lifting jack, comprising a standard, upper and lower runners mounted to slide on said standard, the lower runner being arranged to clutch the standard, an operating lever fulcrumed on the upper runner and having a pitman connection with the lower runner, a dog mounted in the upper runner and spring pressed into engagement with the standard, a cross-pin interposed between a portion of the dog and the adjacent edge of the standard, the upper runner being formed with laterally elongated slots, accommodating the ends of said pin and the runner being further formed with an inclined outer wall, and a releasing lever forked to embrace the runner and pivotally connect the ends of said pin and arranged to ride upon the inclined 20 wall of the runner whereby to draw the dog backwardly against its spring tensioning means, the runner being formed with a groove designed for the reception of said releasing lever whereby to hold the same in released 25 position.

5. A lifting jack, comprising a standard, upper and lower runners mounted to slide in said standard, an actuating lever formed with a trunnion provided with a threaded 30 bore, the upper runner being provided with a bearing opening receiving said trunnion, a screw working in said bore, and arranged to hold the trunnion in said opening, and an operative connection between said actuating 35 lever and the lower runner.

6. A lifting jack, comprising a standard, upper and lower runners mounted to slide on said standard, the lower runner being arranged to grip the standard, an operating lever fulcrumed on the upper runner and having a pitman connection with the lower runner, the upper runner being formed with a cavity, a block rigidly secured in said cavity and formed with a forwardly facing chamber 45 communicating with the rear edge of the standard, and with an upturned lower end producing a socket in the lower end of the chamber, and an outwardly spring pressed dog mounted in said chamber and supported 50 with its lower end in said socket and arranged for engagement with said runner.

7. A lifting jack, comprising a standard, upper and lower runners mounted to slide on said standard, the lower runner being ar-

ranged to grip the standard, an operating lever fulcrumed on the upper runner and having a pitman connection with the lower runner, the upper runner being formed with a cavity, a block rigidly secured in said cavity and formed with a forwardly facing chamber 60 and an upwardly facing socket in the lower end of the chamber, and an outwardly spring pressed dog mounted with its lower end in said socket and supported thereby in said chamber, and means connected to the upper 65 end of the dog for drawing it rearwardly as and for the purpose set forth.

8. A lifting jack, comprising a standard, upper and lower runners mounted to slide on said standard, the lower runner being arranged to grip the standard, an operating lever fulcrumed on the upper runner and having a pitman connection with the lower runner, the upper runner being formed with a cavity, a block rigidly secured in said cavity 75 and formed with a forwardly facing chamber and an upwardly facing socket in the lower end of the chamber, a dog mounted in said chamber and supported with its lower end in said socket and arranged for engagement 80 with said runner, and a leaf spring interposed between the rear side of the dog and the adjacent wall of the chamber and exerting a forward tension upon the dog.

9. A lifting jack, comprising a standard, upper and lower runners mounted to slide on said standard, the lower runner being arranged to grip the standard, an operating lever fulcrumed on the upper runner and having a pitman connection with the lower runner, a dog mounted in the upper runner and spring pressed into engagement with the standard, a releasing lever pivotally connected to the dog, the runner being further formed with an inclined outer rear wall and a 90 groove therein, and the releasing lever being arranged to ride upon said inclined wall whereby to draw the dog backwardly against its spring tensioning means, the lever being further arranged to engage in said groove 95 whereby the lever may be held in released position.

In testimony whereof I affix my signature in presence of two witnesses.
